QUILTING DEVICE

Anthony J. Bieker, Leoti, Kans.

Application September 22, 1937, Serial No. 165,218

1 Claim. (Cl. 45—24)

My invention relates to quilting devices and more particularly to adjustable quilting frames.

One of the principal objects of my invention is to provide a quilting frame equipped with means for readily adjusting the frame members relative to each other to accommodate various size quilts.

Another object of my invention is to provide a quilting device having side frame members equipped with means whereby the side frame members may be adjusted relative to each other during the quilting operation for the purpose of rolling the quilt about one or both of said members in order that the operator may have ready access to the working area.

15 A further object of my invention is to provide a device of the above described character which is simple in construction, easy in operation and durable in use.

Other objects and advantages will be apparent 20 from the following description, appended claim and annexed drawing.

Referring to the drawing wherein like reference characters designate like parts throughout the several views:

25 Fig. 1 is a top plan view of my invention.

Fig. 2 is a sectional view taken on a line 2—2 of Figure 1.

Fig. 3 is a similar view of Figure 2 illustrating the corner device in reverse position.

30 Fig. 4 is a sectional view taken on a line 4—4 of Figure 1.

Fig. 5 is an end elevation of one of the corner devices attached to one of the side members and in reverse position.

35 Fig. 6 is a detail sectional view taken on a line 6—6 of Figure 1 of one of the side members.

In practicing my invention I employ a pair of side members 7 connected to a pair of cross members 8 by means of corner devices 9 to form a 40 quilting frame.

Each of the members 7 and 8 are fashioned with offset ribs 10 and 10' respectively for reenforcing said members and providing inner and outer laterally extending flanges 10a and 10b respectively, the upper face of said ribs 10 and 10' being formed with a plurality of apertures 11 and 11' respectively for a purpose hereinafter described, the apertures 11' formed in the ribs 10' of the members 8 being fashioned with a plane wall section 11a. Each of the members 7 and 8 are also fashioned with openings 12 in the inner flanges 10a thereof for the purpose of receiving basting threads for securing the edges of a quilt to the frame.

45 The corner devices comprise pairs of right and

left units and each unit is formed with a housing 13 fashioned with upper and lower oppositely extending end sections 14 and 14a terminating in hooks 15 and 15a respectively. The lower section 14a, adjacent the housing 13, is offset to form a 5 fold 14b for engagement with the outer flange 10b of a side member 7, while the housing is fashioned with a downwardly projecting portion 13a and has 10 slidably therein a latch bolt 16, one end of said bolt being formed with a finger piece 17 while the 10 opposite end engages one of the apertures 11 in a side member 7 and a similar opening 13b formed in the portion 13a of the housing. The latch bolt 17 has secured therethrough a pin 18, the ends of 15 which support a coil spring 19 interposed between said pin and the wall of the housing, said spring functioning to maintain the latch bolt within the apertures in the rib 10 and housing heretofore described. From the foregoing it will be apparent that the corner devices are latched to the member 20 7 and adjustable lengthwise thereon by operation of the bolt 16.

Secured to the end sections 14 and 14a adjacent the hooks 15 and 15a are locking pins 20 and 20a respectively, the pin 20 extending within one of 25 the openings 11' formed in the rib 10' of a cross member 8 while the hook 15a on the oppositely disposed end section 14a is hooked through another of the apertures 11', the inner folded face 30 of the hook engaging the plane face of the aperture.

In operation, the corner devices are adjusted on the side members by manipulating the latch bolts to register with suitable apertures in the ribs 10. The corner devices together with the side members are adjusted on the cross members 8 by positioning the hooks 15a of the corner devices into suitable apertures 11' formed in the members 8 and snapping the respective locking pins 20 into position in the spaced apertures of the respective members, as clearly illustrated in Figure 2. In this position of the parts, a quilt is basted to the frame as heretofore described and an operator or operators are enabled to quilt the same over areas 35 adjacent the side members 7. When it is necessary to bring an unquilted area of the quilt into operating range, one of the side members is disengaged from the cross members by releasing the locking pins from within their respective apertures and disengaging the hooks from their respective apertures and rotating the side member 40 in a direction to wind the quilt thereon, at 180°. In this position the opposite hooks 15 are engaged within suitable apertures 11' and the opposite 45 50 55

- locking pins 20a snapped into locking engagement with other apertures 11', as illustrated in Figure 3. This operation serves to lessen the distance between the side members and present a new working area next to the adjusted side member. If desired, in the instance where two operators are employed, one working adjacent each side member, the opposite side member may be adjusted in the same manner to present a new operating area of the quilt.
- 10 What I claim is:
- In a quilting device, a frame having side and cross members each formed with spaced apertures, corner devices securing said side and cross members together in spaced relation, at least one of said corner devices fashioned with a housing receiving the end of one of said side members, said housing equipped with a spring pressed latch bolt extending within an aperture in said end of the 15 last mentioned side member whereby to permit longitudinal adjustment of the end of said last mentioned side member relative to the housing upon retraction of said latch bolt from said last

mentioned aperture, said housing formed with oppositely extending end sections each terminating in a hook, one of said hooks engaging within an aperture in a cross member whereby to secure the latter to said last mentioned side member, a locking pin mounted on each of said end sections adjacent their respective hooks and one of said pins extending within another aperture in said last mentioned cross member to lock the latter to said last mentioned side member in a manner 10 whereby disengagement of said last mentioned pin and subsequent disengagement of said last mentioned hook from their respective apertures permits said housing together with said last mentioned side member to be inverted to vary the 15 distance between said last mentioned side member and the other side member of said frame and to secure said inverted side member locked to the last mentioned cross member upon engagement of the other hook and pin on the oppositely disposed 20 end section of said housing in adjacent apertures in said last mentioned cross member.

ANTHONY J. BIEKER.
